United States Patent Office.

EDWARD POWELL, OF CONNEAUTVILLE, PENNSYLVANIA.

Letters Patent No. 60,784, dated January 1, 1867; antedated December 29, 1866.

SPRING CRUPPER.

The Schedule referred to in these Letters Patent and making part of the same.

TO ALL WHOM IT MAY CONCERN:

Be it known that I, EDWARD POWELL, of Conneautville, in the county of Crawford, State of Pennsylvania, have invented a new and improved "Spring Crupper," to keep horses' tails in proper elevation and position when in harness; and I do hereby declare that the following is a full and exact description of the same, reference being had to the accompanying drawings and the letters of reference marked thereon.

Figure 1 represents my invention, with all its parts adjusted in working order, and ready to be buckled by the strap F on to any harness desired.

A A, C C, is a steel or other suitable metal bow, bent at B B in a spiral spring, and continued in a U form at C C, which part, C C, is placed under the tail of the horse, and supports the tail in an elevated position. This crupper can be covered with leather. D D are loop-holes, in which straps are attached, if desired, to buckle around the tail. The part A A rests on the "crupper bone" or "rump" of the horse, as the ordinary crupper rests. The part of the crupper, C C, is so bent as to form an obtuse angle with the part A A, as shown in

Figure 2, which is a side view of the metal bow uncovered with leather.

What I claim as new, and desire to secure by Letters Patent, is—

The metal frame A A, in combination with the spiral spring B B, and tail-supporter C C, substantially as described.

EDWARD POWELL.
